DESIGN FOR A WHIRLING BOWL TOY

Clinton J. Davidson, San Diego, Calif.

Application January 10, 1944, Serial No. 112,202

Term of patent 14 years

(Cl. D34—15)

To all whom it may concern:

Be it known that I, Clinton J. Davidson, a citizen of the United States of America, residing at San Diego, in the county of San Diego and State of California, have invented a new, original, and ornamental Design for a Whirling Bowl Toy, of which the following is a specification, reference being had to the accompanying drawing, forming part thereof.

Figure 1 is an elevational view, partly in sec-

tion, of a whirling bowl toy, showing my new design; Fig. 2 is a side elevational view of the bowl portion shown in section in Fig. 1; Fig. 3 is an edge elevational view of the bowl portion shown in Fig. 1; and Fig. 4 is an elevational view showing the opposite side of the bowl element.

I claim:

The ornamental design for a whirling bowl toy, substantially as shown.

CLINTON J. DAVIDSON.
